UNITED STATES PATENT OFFICE.

GEORGE BESTER McKINNEY, OF BARRY, ILLINOIS.

STOOL.

1,070,278.

Specification of Letters Patent.

Patented Aug. 12, 1913.

Application filed May 29, 1912. Serial No. 700,367.

To all whom it may concern:

Be it known that I, GEORGE BESTER McKINNEY, a citizen of the United States, and a resident of Barry, in the county of 5 Pike and State of Illinois, have invented a new and Improved Stool, of which the following is a full, clear, and exact description.

This invention relates to stools for use by dentists and for other purposes, and has reference more particularly to a device of this 10 class which comprises a suitably formed seat and a mounting for the seat which permits the same to be positively and flexibly adjusted in any direction, and having means 15 whereby the adjustment can be readily controlled.

The object of the invention is to provide a simple, strong and durable stool which can be used for a variety of purposes: which is 20 capable of a number of adjustments: which is so constructed that the user thereof can without difficulty, move it flexibly in any lateral direction, and which can be raised and lowered to any desired height within 25 certain limits.

The invention consists in the construction and combination of parts to be more fully described hereinafter and particularly set forth in the claims.

30 Reference is to be had to the accompanying drawings, forming a part of this specification, in which similar characters of reference indicate corresponding parts in all the 35 figures, and in which—

Figure 1 is a side elevation of a preferred embodiment of my invention: Fig. 2 is an elevated cross-sectional view of the device shown in Fig. 1: Fig. 3 is a transverse sectional view taken on the line 3—3 of Fig. 2: and Fig. 4 is an enlarged sectional view taken on the line 4—4 of Fig. 2.

Before proceeding with a more detailed description of my invention, it is to be understood that the shape of the seat may be varied in accordance with special conditions and the general relation of the parts may be differently arranged without departing from the underlying spirit of the invention.

50 Referring more particularly to the drawings, I provide a base 1 of upwardly tapered form and having the bottom thereof suitably proportioned to provide a firm support for the stool. The base is hollow and has at 55 the upper end, an opening 8. It is provided

about its upper edge with lugs 2, 2 spaced equi-distant and provided with studs 2^a. Flexible members 3 engage the studs 2^a of lugs 2 and consist of rods 3^a and helical springs 3^b, so that, in effect, the flexible members are compressible but tend to maintain their normal dimensions. A post 7 of tubular form is associated with the base and extends into the same through an opening 8. A sectional sleeve 4, comprising a plurality of substantially segmental cross-section members, is adjustably mounted upon the post and has pairs of spaced equi-distant lugs 4^a, between which the upper ends of the flexible members 3 are pivotally secured. An open bracket 5 is associated with the sleeve and embraces the same, having a rounded part secured thereto by means of rivets 5^a, or in any other suitable manner. Opposite the rounded part, the bracket has an angularly-disposed part provided with a threaded opening 5^b, in which is received a correspondingly threaded adjusting rod 6, having a handle by means of which it can be conveniently manipulated, and a rounded clamping head 6^b adapted to engage the sectional sleeve, so that the latter can be readily clamped upon the post.

The base is provided at the inside near the upper part thereof, with a helically-grooved socket 1^a, in which is mounted a strong helical spring 13 extending downwardly from the upper portion of the base. A head 12 is supported within the spring at 85 the lower end thereof, by means of a helically-grooved extension which engages the lower coils of the spring. The head 12 is tubular and receives the support which is provided with a laterally-extended flange 90 13^a engaging at the upper rim of the head. An annular plate 11 is positioned under the head 12 about the lower end of the support 7 and rests upon an annular collar 9, having at the upper edge a laterally-disposed flange. The collar has openings which register with 95 corresponding openings in the tubular support and with the same receive a cotter pin 10 or like member for holding the parts in place.

A pin 16 is arranged within the tubular support at the lower end thereof and is mounted in suitable openings at the side of the support. A keeper 14, consisting of an elongated bar, is pivotally mounted upon the 110

pin 16 and has the upper end laterally disposed to engage in any one of a plurality of spaced superposed openings 18 formed in the wall of a tubular post 17 telescopically and 5 slidably received within the correspondingly formed outer post 7. A U-shaped spring 15 has at the ends, coils by means of which it is mounted upon the pin 16 and extension engaging the wall of the support. 10 The spring likewise engages the keeper 14 and tends to displace the same from engagement with the openings 18. A releasing member 19, consisting of a bar having the upper end laterally disposed, extends into 15 the tubular support 17 through the upper end thereof, being pivotally mounted upon a pin located for the purpose at the upper end of the support. The laterally-disposed extremity 23 of the releasing member constitutes a handle by means of which it can be 20 manipulated.

The seat 22 of the stool may be of any suitable form, size and shape. It is preferably provided with a concave supporting member secured at the under side thereof by 25 means of screws or rivets, and provided with an internally-threaded boss by means of which it is screwed upon the corresponding threaded upper end of the inner post 17. 30 The extremity 23 of the releasing member extends through an opening 24 in the part 21. A spring bar 20 is secured to the releasing member and engages within the supporting element 21 and tends normally to 35 hold the releasing member in a position such that the keeper is operable.

To raise or lower the seat, the keeper 14 is released by suitably lifting the handle 23 of the releasing member, to displace the 40 lower end of the bar 19 from the keeper. This permits the spring 15 to disengage the keeper from one of the openings 18, so that the stool can be easily raised or lowered to its desired height, thereupon the 45 releasing member is set free, so that it will again press the keeper against the side of the tubular post to bring the laterally-disposed upper part of the keeper into engagement with the corresponding opening 18.

50 It will be readily understood that the spring 13 forms a resilient hanger for the telescopic seat support, and the opening 18 is so proportioned that the support can be flexibly disposed in any lateral direction. 55 The spring 13, furthermore, provides the stool with a vertical, flexible support and renders its use comfortable and pleasant. The lateral flexibility of the stool support is also controlled through the members 13 60 and their adjustable connection with the outer post, and, as will be readily understood, the rotary motion of the stool is not obstructed by any member connected to the tube 7 when the segments are not clamped 65 thereto.

Having thus described my invention, I claim as new and desire to secure by Letters Patent:

1. A stool, comprising a base, a flexible support associated therewith, a post carried by said support, said support permitting said post to move in any lateral direction, a seat carried by said support, and an additional flexible connection between said base and said post and comprising spring supports 70 extending upwardly from the base and having an adjustable connection with the post.

2. A stool, comprising a base, a flexible support depending therein, an extensible post having its lower end extending within and carried by said support and provided with means for securing it in different adjustments, said support permitting said post to move in any lateral direction, a seat carried by said support, and an additional flexible connection between said base and said post and having an adjustable connection 80 with the latter.

3. A stool comprising a base, a post having its lower end supported by and movable with respect to, the said base, spring supports having bearings on the base and extending upwardly therefrom in a series around the post, a sectional collar forming a split and slidable sleeve on the post, and to the sections of which the upper ends of said spring supports are connected, and means on the said sleeve whereby the latter is rigidly held upon the post, substantially 90 95 100 as described.

4. A stool, comprising a hollow base, a post, means for supporting the post in the base to permit it to move laterally, a seat carried by the upper end of the post, a sleeve adjustably secured on the post above the base, and spring supports disposed between said sleeve and said base and arranged in a series around the post.

5. A stool, comprising a hollow base, a helical spring and having its upper end secured to the upper end of the base and depending within the same, a tubular head carried by the lower end of the spring, a post having its lower end secured in the said head and projecting through the spring above the base, and a seat provided with a post adjustably secured to the first named post.

6. A stool, comprising a hollow base having a helically grooved inner surface adjacent its upper end, a helical spring member having its upper convolutions disposed within said groove and its lower portion freely depending within the hollow of the base, and an annular plate disposed at the lower end of the said spring and having a tubular head projecting upwardly within the spring and provided with a helically grooved surface engaging the lower convo- 110 115 120 125 130

lutions of the said spring, a post depending through the base within the said spring and having its lower end projecting through the said annular plate and its tubular head and 5 provided with projections above the head and below the said annular plate, and a seat carried by the upper end of the post.

In testimony whereof I have signed my name to this specification in the presence of two subscribing witnesses.

GEORGE BESTER McKINNEY.
